UNITED STATES PATENT OFFICE.

DAVID B. RODKEY, OF WILKINSBURG, PENNSYLVANIA.

GLOVE-CLEANING MACHINE.

1,143,440.

Specification of Letters Patent.

Patented June 15, 1915.

Application filed May 9, 1914. Serial No. 837,488.

To all whom it may concern:

Be it known that I, DAVID B. RODKEY, a citizen of the United States, residing at Wilkinsburg, in the county of Allegheny and State of Pennsylvania, have invented new and useful Improvements in Glove-Cleaning Machines, of which the following is a specification.

Specifically considered, the invention is primarily intended to devise a machine for cleaning gloves, however, it is not restricted in its application since it may be adapted for cleaning sundry small articles.

The invention consists of a vat or tank which is adapted to contain a cleansing bath, an endless carrier having a portion arranged to dip into the bath for immersing the articles to be cleansed. Suitable supporting means for the endless carrier including a take-up device whereby any slack in the carrier may be compensated for; and a pair of cleaning rolls or brushes arranged upon opposite sides of a portion of the endless carrier in such a manner as to cause the articles to pass between them during the process of cleaning, said articles being alternately immersed in the bath and subjected to the action of the cleaning rolls or brushes.

30 The invention consists of the novel features, details of construction and combination of parts, which hereinafter will be more particularly set forth, illustrated and claimed.

35 In the drawings hereto attached: Figure 1 is a side view of a glove cleaning machine embodying the invention. Fig. 2 is a vertical central longitudinal section. Fig. 3 is a top plan view. Fig. 4 is a transverse section on the line $x-x$ of Fig. 3. Fig. 5 is a detail view of one of the work holders.

40 Corresponding and like parts are referred to in the following description, and indicated in all the views of the drawings, by the same reference characters.

The tank or vat for containing the bath may be of any capacity and its opposite ends flare as indicated at 1 and in order to give stability, a suitable stand 2 is provided and 45 preferably forms a part of the vat or tank structure. The sides of the vat or tank are parallel. An endless carrier 3 is arranged to operate in the tank and its lower portion is deflected so as to dip into the bath and 50 immerse the articles therein to be cleansed. The endless carrier 3 preferably consists

of two belts which are spaced apart and support work holders 4 which in turn serve to connect the belts or members comprising the endless carrier. Shafts 5 and 6 are located at opposite ends of the tank and each is provided near its ends with sprocket pulleys which receive and support the endless belts, the latter being provided with openings to receive the teeth of the sprocket pulleys so as to insure positive movement of the belts. The shaft 5 is mounted in fixed bearings whereas the shaft 6 is mounted in bearings which are adjusted by means of screws 7 and adjusting nuts 8, whereby provision is had for taking up slack. A shaft 9 is located near the bottom of the tank and is provided near its ends with pulleys beneath which pass the lower portion of the belts comprising the endless carrier. It will be observed that the lower portion of the endless carrier inclines in opposite directions, the inclination conforming approximately to the inclination of the ends 1 of the tank. The upper portion of the endless carrier passes over idler pulleys 10 which are located centrally of the tank and at the sides thereof. The power for operating the endless carrier is applied to the shaft 5 by means of a belt pulley 11 which is secured to one end thereof. A pair of cleaning rolls or brushes 12 and 13 are located at the upper portion of the tank at a middle point, in such position as to receive the upper portion of the endless carrier between them. This pair of cleaning rolls or brushes is located intermediate of the idlers 10. The roll or brush 13 is positively driven by means of a belt 14 which passes around a pulley 15 secured to one end of the shaft 5 and a pulley 16 secured to a projecting end of the shaft or journal of the member 13. The cleaning member 12 is arranged beneath the upper portion of the endless carrier and is mounted in fixed bearings and is driven from the pulley 15 by means of a belt 12^a which passes around a pulley 12^b fastened to a projecting end of the shaft or journal of the member 12. The cleaning member 13 is located above the upper portion of the endless carrier and is mounted in bearings which are yieldable vertically and are pressed downward by means of springs 17 whose tension is adjustable by means of nuts 18 mounted upon screws 19. 105 The cleaning member 13 is located directly above the cleaning member 12 and is rotated 110

in an opposite direction thereto. The upper portion of the vat and the rotary cleaning mechanism are closed by means of a suitable cover. The work holders comprise 5 lower members 20, upper members 21, and screws 22. The members 20 and 21 consist of strips, 20 being secured at their ends to the belts comprising the carrier and the strips 21 being hinged at one edge to the strips 20. The screws 22 clamp the strips 21 to the strips 20 and secure the work between the two strips or members.

The bath supplied to the tank or vat will depend upon the nature of the work and 15 may consist of soap and water, gasolene or other liquid. The gloves or other articles to be cleansed are attached to the holders 4 by being clamped between the members thereof after which the endless carrier and 20 rotary cleaners are set in motion. In the operation of the machine the articles are alternately immersed in the cleansing bath, thence subjected to the action of the rotary cleaners and this process is continued until 25 all the soil is removed, after which the articles are detached from the work holders 4 and subsequently rinsed or otherwise cleansed preliminary to being dried and finished.

30 From the foregoing description, taken in connection with the accompanying drawings, the advantages of the construction

and of the method of operation will be readily apparent to those skilled in the art to which the invention appertains, and 35 while I have described the principle of operation of the invention, together with the device which I now consider to be the best embodiment thereof, I desire to have it understood that the device shown is merely 40 illustrative, and that such changes may be made when desired as are within the scope of the invention as claimed.

Having thus described the invention, what 45 is claimed as new is:—

In a cleaning machine, a tank, a roller journaled therein adjacent the bottom thereof, spaced pairs of rollers journaled in the upper ends of the tank at opposite sides of the first mentioned roller, spaced endless carriers passing around said rollers, work holders comprising upper and lower hingedly connected parallel members disposed transversely of the tank and connecting said endless carriers, a set screw for locking said 50 members together, and cleaning mechanism comprising complemental members between which said endless carriers pass.

In testimony whereof I affix my signature in presence of two witnesses.

DAVID B. RODKEY.
